DESIGN FOR A TOWEL RACK

Benjamin Sadowski, Chicago, Ill.

Application March 6, 1944, Serial No. 112,807

Term of patent 7 years

(Cl. D33—16)

To all whom it may concern:

Be it known that I, Benjamin Sadowski, a citizen of the United States of America, residing at Chicago, in the county of Cook and State of Illinois, have invented a new, original, and ornamental Design for a Towel Rack, of which the following is a specification, reference being had to the accompanying drawing, forming a part thereof.

Fig. 1 is a top plan view of the towel rack, showing my new design;

Fig. 2 is an enlarged side elevational view of one of the bracket members of the towel rack; and

Fig. 3 is an end elevational view thereof.

I claim:

The ornamental design for a towel rack, as shown.

BENJAMIN SADOWSKI.
